UNITED STATES PATENT OFFICE.

HUGH H. CRAIGIE, OF STAMFORD, CONNECTICUT.

WATER-CLOSET.

SPECIFICATION forming part of Letters Patent No. 397,781, dated February 12, 1889.

Application filed August 20, 1887. Serial No. 247,405. (No model.)

To all whom it may concern:

Be it known that I, HUGH H. CRAIGIE, of Stamford, Fairfield county, Connecticut, have invented certain new and useful Improvements in Water-Closets, of which the following is a specification.

My invention relates to those two classes of closets known as "siphon-closets" and "wash-out closets," more especially to siphon-closets in which a large siphon-passage between the bowl and the sewer-pipe acts to rapidly evacuate the bowl when flooded by a sudden flush of water. In these closets water is usually discharged down into the bowl through the flushing-rim at the top, and also in an upward jet through the ascending limb of the siphon, which jet acts to start and flood the siphon, while the discharge from the flushing-rim cleanses the bowl, and the joint action of both causes a rapid evacuation of the bowl through the siphon.

In my improvement I provide the interior of the bowl with a vertical water channel or gutter running down one side, preferably the front side, and in a line with the ejecting-aperture and the siphon, into which channel the water-flush is discharged, and, descending in an energetic stream into the water-pool in the bottom of the basin, renders the surging, cleansing, and evacuating action of the flush much more certain and effective. This channel preferably issues from the flushing-rim, and is supplied therefrom at a point opposite to the attachment of the water-supply pipe. The water-supply or flushing pipe connects to a large distributing hub or neck on the edge or rim of the basin, which communicates with the vertical channel through the usual flushing-rim or otherwise. The upward jet in the ascending limb of the siphon is connected with this hub through the medium of a distinct tube leading downward from said hub to the jet, exteriorly of the siphon, and preferably of earthenware, integral therewith.

In the drawings annexed, Figure 1 presents a side elevation of a siphon-closet embodying my invention, and Fig. 2 is a section thereof. Fig. 3 is an elevation of the reverse side, partly in section. Fig. 4 is a plan view, partly in section. Fig. 5 is a rear elevation. Fig. 6 is a vertical section similar to Fig. 2, and showing a modified construction. Fig. 7 is a

plan of a wash-out closet embodying my invention, and Fig. 8 is a vertical mid-section thereof.

I will first describe the construction of siphon-closet shown in Figs. 1 to 5, wherein—

a indicates the bowl or basin of the water-closet, which is made in the usual bowl or urn shape.

b is the ejecting-aperture in the bottom of the bowl, and *c d* the siphon leading from said aperture to the discharge-neck *e*, which is adapted to connect directly to the soil-pipe, as usual in siphon-closets. Now, at the top or rim of the bowl, just above the bend of the siphon, is arranged a large hollow hub or flushing-pipe connection, *f*, (seen best in Figs. 4 and 5,) one end of which is closed, while the opposite end is open to connect with the flushing-pipe, which is coupled therewith in any suitable manner. The side of this hub or cylinder opens into the hollow flushing-rim *g* of the bowl, which encircles the top edge of the bowl in the usual manner. A downward opening, *i*, is formed in this flushing-rim at the front side of the bowl or diametrically opposite to the hub *f*, through which the water will be discharged from the rim down the sides of the bowl. Coincident with this discharge-opening *i* in the rim I prefer to form the bowl with a channel or gutter, *k*, recessed into the wall of the bowl and descending the same vertically to the base of the bowl into the discharge-aperture *b* and in line with the siphon *c d*, as well shown in Figs. 2 and 4, also in Figs. 1 and 3. This channel *k* preferably increases in depth toward the base, it being nearly the same depth as the limb of the siphon where it opens into the discharge-aperture *b*, as well shown in Fig. 2, and the bottom of the channel is preferably in a line or curve continuous with the bottom wall of the ascending limb *c* of the siphon, as seen in Fig. 2, so that a stream descending the channel will tend to flow straight into the limb of the siphon, as will be understood from Fig. 2.

At the mouth of the ascending limb *c* of the siphon, or just where it blends into the aperture *b*, there is an upwardly-directed jet-hole, *n*, which opens from a small cavity, *n'*, in the central line of the basin, which cavity communicates with one end of a distinct exterior pipe or conduit, *m*, the opposite end of which

issues from the lower side of the water-hub *f* and descends therefrom to the jet-cavity along side the siphon, as fully shown in Figs. 3, 4, and 5, and thus conducts free supply of water 5 from the distributing hub or cylinder *f* to the jet *n*, as will be understood. On the side of the distributing-hub *f* is a lateral outlet, *s*, just over the crest of the siphon, which is connected by an elbow-pipe, *o*, with a jet-aperture, 10 *p*, in the top of the descending limb *d* of the siphon, thus forming a downwardly-directed jet in the descending limb, which is also supplied from the distributing-hub *f*.

r is an outwardly-opening flap or check 15 valve in the elbow-pipe to permit the free outflow of water to the jet, but prevent the return-flow of any sewer-gases.

The closet, as described and shown, is made of crockery in one integral piece or structure, 20 as best illustrated in Fig. 2, the elbow-pipe *o* and its valve *r* being preferably made of brass cemented in place, as shown; but other materials or modes of construction may of course be used.

25 In a practical closet the aperture *b* will be of four inches diameter, and the siphon *c d* of similar cross-section. The upward jet, *n*, will be seven-eighths of an inch, and the downward jet *p* the same, while the pipe *m* 30 will have a bore of one inch. The distributing-hub *f* will be two inches in diameter, and will thus be of greater area than all the orifices issuing or supplied from it, and thus supply all of said branches freely, and this 35 hub will be connected by a two-inch pipe in the usual way with a supply-tank adapted on the depression of a pull to supply a voluminous flush of water to the closet at the several points indicated, so as to wash the bowl, 40 flood the siphon, and cause the bowl to be energetically evacuated, while the "after-wash" from the tank will fill the bowl to the sealing-level. Tanks of this character are various and well known, and therefore do not 45 need to be illustrated in connection with the closet to which my invention is confined.

The general construction being, therefore, now set forth, the operation will be readily understood. When the closet is at rest, the 50 after-wash from the tank will suffice to fill the bowl to the level of the dotted line in Fig. 2, which is coincident with the top of the separating-partition of the siphon-limbs, and this bowl of water will effectually seal the 55 closet. Any slight excess dripping into the bowl will of course trickle over the siphon-partition down into the long limb of the siphon, and thence into the sewer-pipe without flooding the siphon, which flooding will only 60 take place by a sudden voluminous discharge of water in the bowl or siphon. As soon, however, as the flush of water is admitted from the tank it will first enter the distributing hub or cylinder *f* and be thence distributed therefrom in three branches—viz., 65 from the flushing-rim through the aperture *i*, down the sides of the bowl, and through

the channel *k* into the water-pool and directed toward the aperture *p* and the siphon; secondly, in an energetic upward jet 70 from the jet-hole *n* up into the ascending limb *c* of the siphon, and, thirdly, in a downward jet from the jet-hole *p* down into the descending limb of the siphon. The water descending the side of the bowl from the 75 flushing-rim will not only partly spread over the inner surface of the bowl and thus cleanse the same, but will be concentrated chiefly in a powerful stream rushing down the channel *k* into the water-pool below, in which it will 80 produce such an effective surge and agitation as to quickly submerge the paper or other floating matter, and its stream being delivered in a direction across the aperture *b* and into the siphon *c* will tend to eject the 85 contents through the siphon, and thus greatly assist the siphoning action. The water flowing into the bowl, as described, through the channel *k* will thus not only produce an effective cleansing, surging, and submerging 90 action, but will flood the bowl and raise its water-line above the normal level, and thus tend to flood the siphon, which will be positively effected by the joint action of the upward and downward jets *n p*, the upward jet 95 acting as an injector to project the water up through the siphon, and thus causing the siphon to fill and act energetically to evacuate the entire contents of the bowl in a sudden and powerful manner. The downward jet of 100 course acts to at first project the air from the descending limb, and thus greatly assists the action of the upward or main jet *n* in causing the siphon to fill and operate quickly, and both jets act, of course, as positive ejecting- 105 jets in each limb, adding to the natural siphoning action of the water-columns therein, and thus tending to break up and propel through the siphon any paper or solid matter in the contents of the bowl, so that the combined action of the three water-streams and the siphon-column renders the cleansing and evacuating action of the closet peculiarly 110 quick, energetic, and complete.

It will be noted that three streams are delivered at different points in the closet, all 115 supplied from one main distributing-cylinder or reservoir-hub, *f*, at the top of the closet, to which the flushing-pipe connects. The main or upward siphoning-jet *n*, as will be noted, 120 is supplied through a distinct exterior conduit, *m*, descending from the distributing-hub *f* to the jet alongside the siphon, this conduit being preferably made in crockery integral with the remainder of the closet structure, as 125 shown in Figs. 3 and 5. This construction avoids an internal channel in the bowl, which would be more difficult and expensive to construct, and provides a freer passage for the water without increasing the bulk of the bowl. 130

The exterior conduit, *m*, is arranged at and extends throughout its length along the angle formed by the junction of the bowl with the short leg of the siphon, whereby it is pro-

tected from injury, and, being formed integrally therewith, it is not only strengthened itself, but it contributes also to the strengthening of the bowl and siphon.

5 It is to be observed that the flushing connection or hub *f* is located beneath the top of the bowl, so that it does not increase the height of the closet, and above the water-level in the bowl, and that while the jet-passage *m* leads directly downward from it the passage communicating with the flushing-rim extends upwardly from the hub *f*, as clearly shown in Fig. 2; hence the jet-water flows with greater force than the flushing-water and is more immediate in its action, since the hub *f* must be filled with water before any material quantity of water will rise into the flushing-rim. Thus the jet *n* begins to act upon the siphon before the level of water in the bowl is raised above 20 the normal, thus hastening the evacuation of the closet.

It will be readily understood that the different features of my invention may be used separately, and need not in all cases be combined to act jointly, as shown in the drawings. For example, the channel *k* and upward jet *n* may be used without the downward jet *p*, an example of which is shown in Fig. 6, and the channel *k* may be used with 30 out either jet, and so on in various combinations or arrangements. Experience has shown that the construction shown in Fig. 6 is quite effective and practically as advantageous as that shown in the preceding figures.

35 The channel *k* may of course be used in "wash-out" closets or in any other type of closet for which it is adapted, whether operated by siphon or not, as its use is not of course confined to siphon-closets.

40 Figs. 7 and 8 show a common form of wash-out closet to which my invention is in part applied. The outlet *b* from the bowl is at the rear over a dam, *q*, which retains a pool of water in the bowl, and from the outlet a soil 45 passage, *d*, leads down to the neck *e* at the floor. The channel *k* is constructed substantially the same as in the previous figures from the opening *i* in the flushing-rim down to the lowest point in the bowl, the only difference 50 being that it is not so deep. Its depth increases until the lowest point is reached, after which, as it is continued rearwardly in an uninterrupted sweep to the outlet *b*, it gradually decreases in depth, so that the same effect is 55 produced as in the construction first described by the continuation of the sweep of this channel into the siphon-limb *c*. In either construction the flushing-rim *g* may be slotted in the usual manner for discharging the water down the sides of the bowl, or it may have 60 no other opening than the opening *i*.

I of course do not limit myself to a hollow or flushing rim for conducting the water-supply to the channel *k*, as the supply may be 65 conducted thereto in any other suitable way.

It will be understood that the siphon *c d* also acts as a trap, and may be so considered.

I am well aware that water-closet bowls have been made with an internal tube or passage within the wall of the bowl descending 70 from the flushing-rim and opening into the bowl under the level of the water therein; but this is distinct from my improvement, which employs a superficial channel or gutter, *k*, on the inner surface of the bowl descending 75 from the flushing-rim to the base of the bowl, for in this case the stream of water is discharged down the inner surface of the bowl itself and strikes the pool of water in the bowl from the surface downward, which not 80 only keeps an important part of the surface of the bowl cleansed, but, as the stream strikes the surface of the water in the bowl, it produces a much greater commotion therein, which acts to more rapidly submerge 85 paper or other floating matter, and thus renders the ejecting action of the closet much more rapid and cleanly.

What I claim as my invention is—

1. A water-closet bowl or receptacle formed 90 with an open channel or gutter sunk in its inner surface, and extending from or near the rim to the base of the bowl and directed toward the discharge-aperture, with a water-duct arranged to discharge into said channel, 95 substantially as set forth.

2. A water-closet bowl having a hollow flushing-rim at the top and a discharge-aperture with an open water-channel sunk in the inner surface of the bowl, and descending 100 from the rim to the base and directed toward the discharge-aperture, with a water-supply conduit connecting to the hollow rim and a discharge-aperture leading from said rim to said channel, substantially as set forth. 105

3. A water-closet bowl or receptacle formed with an open vertical channel on the inner wall of the bowl descending from or near the rim, directed toward the discharge-aperture, and made of a depth increasing toward its 110 lowest point in the bowl, substantially as shown and described.

4. In a water-closet, the combination, with the bowl or receptacle having a discharge-aperture at the base and a siphonic discharge 115 tube or trap leading therefrom, of a water channel or gutter on the inner wall of the bowl descending the same toward and into the discharge-aperture and in line with the limb of the siphon or trap, and open on the 120 face of the bowl from end to end, substantially as herein set forth.

5. A water-closet bowl having the discharge-aperture *b*, the curved discharge-tube *c*, and the open channel *k*, arranged substantially as 125 shown, with the bottom of the channel of continuous and coincident curve with the bottom of the tube *c*, and blending into and crossing the aperture *b*, substantially as shown and described.

HUGH H. CRAIGIE.
